UNITED STATES PATENT OFFICE.

HENRY R. SWARTLEY, JR., OF GREAT NECK, AND LOUIS LARSEN, OF BROOKLYN, NEW YORK, ASSIGNORS TO DAVIS-BOURNONVILLE COMPANY, OF JERSEY CITY, NEW JERSEY, A CORPORATION OF NEW YORK.

AUTOMATIC SAFETY SYSTEM FOR ELECTROLYZERS.

1,201,526.

Specification of Letters Patent.

Patented Oct. 17, 1916.

Application filed July 21, 1916. Serial No. 110,464.

To all whom it may concern:

Be it known that we, HENRY R. SWARTLEY, Jr., and LOUIS LARSEN, citizens of the United States, residing, respectively, at 5 Great Neck, Long Island, in the county of Nassau and State of New York, and borough of Brooklyn, in the county of Kings and State of New York, have invented certain 10 new and useful Improvements in Automatic Safety Systems for Electrolyzers, of which 15 the following is a specification.

In the electrolysis of water for the commercial production of oxygen and hydrogen great care must be exercised to keep the 20 gases separated during and after liberation, in order both to preserve the purity of the product and to avoid highly dangerous explosions. To this end the electrolyzer cells are specially designed so as to prevent migration and mingling of the gases therein; but these precautions do not safeguard 25 against the condition which arises in event of the dissociating current flowing in the reverse direction to that intended, in which case hydrogen is liberated at the oxygen 30 electrode and oxygen at the hydrogen electrode, the gases thence passing into the education systems, eventually to reach the gasometers, compressing apparatus and pressure storage tanks, where the presence of explosive mixtures is likely to be especially disastrous.

The passage of the electrolyzing current in the wrong direction through the cell may 35 result from a number of causes, among them disturbances in the power station from which electrical energy is obtained or in the transmission lines, or transposition of connections at the electrolytic plant, or reversal 40 of the dynamo connected with the electrolyzer cells. The last condition may be produced, among other ways, by discharging of the electrolyzer when the plant is shut down, such discharge current flowing 45 through the external circuit and dynamo in the opposite direction to the dissociating current, and being capable, under some circumstances, of reversing the polarity of the dynamo, so that when the plant is again 50 started up it will generate current of reverse polarity. In addition to this possibility, permitting cells of this kind to discharge is injurious to the cells themselves, and more especially to the anodes thereof, which are

usually of iron nickel plated and are not 55 adapted to withstand repeated reversals.

With the above in view the object of the invention is to provide a safety system which will not permit the electrolyzers to operate under improper conditions and which will 60 prevent discharging.

Two embodiments of the system will now be briefly described, it being understood however that various other modifications may be designed.

In the accompanying drawings: Figure 1 is a diagrammatic view of a water-electrolyzer plant showing a form which the safety system may take where the voltage of the line wires is too high for the cells, or where 70 they carry alternating current and a motor-generator set is therefore employed; and Fig. 2 is another diagram showing how the system may be adapted for direct connection with the line wires of a direct current 75 distributing system. Another possibility would be an isolated electrical generating plant, in which case the dynamo supplying the electrolyzing current would be driven by a steam engine or any prime mover.

In Fig. 1 the current for decomposing the water is generated by a dynamo D driven by an electric motor M. The motor is included in a circuit 4 across the line, and is shown for simplicity as shunt wound, 85 though a compound wound or an alternating current motor may be employed. A motor starter is represented diagrammatically by the resistances R¹, R², R³, and switches S¹, S², S³ and S⁴. Any starter may 90 be used either manual or automatic, and it will be understood that in starting the resistance coils are cut out in the order of their numerals, and in stopping, in the reverse order. For convenience the starter may 95 be assumed to be automatic, in which case the shunt circuit 5 represents the circuit for controlling the starter, and the coil C¹ therein is symbolic of suitable magnetic means whereby the switches are actuated in proper 100 sequence upon closing the line switches S²⁰, S²¹, and the starter circuit switch S⁷. The nature of the different types of starters being well understood, it is not thought necessary to obscure the diagram with a full 105 representation of the construction and wiring of one of these devices. Switches S⁵ and S⁶ are placed in the starter circuit for

a purpose hereinafter set forth, and opening of either of these switches will deenergize the starter so as to stop the motor and shut down the plant.

5 A battery of water electrolyzer cells is represented at E, and 6 is its external circuit supplied by the dynamo D. Each of these cells comprises electrodes (anode and cathode), whereon the constituent gases, 10 oxygen and hydrogen, are liberated, and embodies provisions for keeping the gases separate, and for conducting them away through eduction systems 7 and 8. For a completer understanding of the nature and operation 15 of such cells reference may be had to the patent of George Halter, No. 1,172,887, of Feb. 22, 1916, for electrolytic plant, it being understood, however, that the present invention is not confined to any one particular 20 type of water electrolyzer.

The electrolyzer circuit is opened and closed by a main electromagnetic switch S¹⁹, the coil C² of which is in a circuit 9 in derivation to the motor circuit and adapted to be 25 closed by the starter at or about the end of the starting operation, so that the dynamo circuit is not closed until the motor which drives is up to speed. For this purpose the circuit 9 is shown provided with a terminal 30 contact 10, in position to be contacted by the last starter switch S⁴ when the latter is closed.

Two electro-magnetic switches S¹³ and S¹⁴ hereinafter referred to, located in circuit 9, 35 and closed during the normal operation of the plant also control the main switch S¹⁹, opening of either one of them deenergizing the coil C² and causing the main switch to drop.

40 Means are provided for stopping generation of the gases in event of the dissociating current starting to flow in the wrong direction through the electrolyzer. The said means preferably comprises a polarized relay R¹, the coil C¹⁵ of which is connected with the electrolyzer circuit, and which controls suitable means for stopping the operation of the electrolyzer. This relay is preferably, though not necessarily of the type of 45 construction familiar in milli-voltmeters, consisting essentially of a pivoted coil C¹⁵ in the field of a permanent magnet 11. When the current is in the right direction the reaction between the coil and the magnet 50 causes the former to hold the movable switch number S¹⁸, which is mechanically united therewith, against the stationary contacts of a break in a relay circuit 12. When no current flows the switch is also held closed by a 55 light weight or spring 13, but if the current passes in the wrong direction for any reason the coil C¹⁵ turns so as to open the switch. The said relay circuit includes the coil C² of a relay R² which normally holds 60 the switch S¹⁸ heretofore mentioned closed.

Consequently opening the polarized relay by a reverse flow in the electrolyzer circuit causes the main switch S¹⁹ in the electrolyzer circuit to open, thereby stopping all generation of gases. For further safety the relay R² 65 may open a switch S³⁰ in the motor starter current. This relay may also operate a signal circuit 35, to give warning when the electrolyzer shuts down.

The polarized relay R¹, upon becoming de- 75 energized, tends to close again, which would result in the electrolyzer circuit closing, only to reopen the polarized relay and thereby the main switch, with a repetition of these operations until the motor generator set was 80 shut down by hand. To avoid these fluctuations the polarized relay could be arranged to stay open, but a preferable device is to construct the relay R² so that it must be reset by hand in order to close the switch S¹⁸ 85 after this relay has once been deenergized. To this end the core of the said relay is connected with a switch S¹⁷ which opens another break in the relay circuit 12 at the same time that switch S¹⁸ opens the circuit 9 controlling the main switch S¹⁹. Consequently the polarized relay may close without causing closing of the circuits 12, 9 and 6, which will not again be closed until the relay R² is raised by its handle 14. 95

The polarized relay R¹, it will be noted, is connected with the electrolyzer circuit at the electrolyzer, rather than with some other part of the circuit, which would be the case if its connections were made on the switchboard, as would be natural. This is important because it is the electrolyzer and not the external circuit which requires protection from reverse flow, and by connecting the relay with the electrolyzer such flow 105 cannot take place under any circumstances, for example, even if the electrolyzer is improperly connected in the circuit. To this end the shunt or resistor 15, employed in connection with this type of relay, is represented as secured as an extension to one of the terminals of the battery of cells, but it may obviously be built into the electrolyzer or mounted in fixed relation thereto in other ways. The relay itself may be located on 115 the switchboard, its coil being connected with the terminal blocks of the shunt by conductors 16.

The relay circuit 12 may also be controlled by a normally closed overload switch S¹⁵, 120 the coil C² of which is connected in series in the electrolyzer circuit. The purpose of this switch, as will readily be understood, is to open the electrolyzer circuit in event of too heavy a current passing. 125

Means are also provided for preventing discharge of the electrolyzer in event of the potential of the dynamo falling so low that it will not overcome the counter electromotive force of the cells. This may be ac- 130

complished by a potential relay R^3 the coil of which is connected in a circuit 17 across the two sides of the dynamo circuit. This coil operates the switch S^{14} in circuit 9, and thereby controls the main switch S^{19} , the switch S^{14} remaining closed as long as the voltage of the generator is sufficiently high and opening when the voltage falls below a predetermined safe value.

10 The oxygen and acetylene pipes 7 and 8 leading from the cells deliver the gases into separate gasometers 18 and 19, from which compressors 20 and 21 driven by motors 22 and 23 compress the gases into pressure tanks 24 and 25. These motors are represented as connected across the line in circuits 26 and 27, each containing two switches S^9 , S^{10} and S^{11} , S^{12} . The switches S^9 and S^{10} constitute upper and lower limit switches operated by the oxygen gasometer 18, and switches S^9 and S^{12} bear a similar relation to the hydrogen gasometer 19. The switches S^{10} and S^{11} are adapted to be opened by pressure responsive devices 28 and 29 connected with the respective pressure tanks, these devices being adjusted to open the corresponding switches when the pressures in the tanks reach a predetermined maximum. It will therefore be understood 30 that when the gasometers are full the rising bells open the switches S^9 and S^{10} , thus stopping the main motor M and shutting down the plant. When thereafter, the operation of the compressors has withdrawn gas from 35 the gasometers, so that their bells descend, the switches S^9 and S^{10} are again closed, and if the generation of gases from the gasometers continues too far, the switches S^9 and S^{10} are opened by the descending bells 40 thereby stopping the compressor motors, which start again when the gasometer bells rise. When the compressors have operated for a sufficient length of time to build up the maximum pressure permitted in the 45 tanks, the devices 28 and 29 open the compressor motor circuits, with the result of stopping the compressing action. When, now, the gasometer bells rise to their upper limit because gas is no longer being withdrawn therefrom by the compressors, the switches S^9 and S^{10} are opened and the electrolyzer put out of action as already described.

In Fig. 2 the line current is used in the 55 electrolyzer. Consequently the motor-generator set and some of the circuits and devices of Fig. 1 are unnecessary, but the wiring and relations may be otherwise similar, and are so shown.

60 The electrolyzer circuit 6^a is connected across the line and is provided with a variable resistance or its equivalent 30 to adjust the current to the needs of the cells. The coil C^2 of the main switch is in a circuit 9^a , 65 which in addition to the switches S^{13} and

S^{14} , also contains the upper limit gasometer switches S^9 and S^{10} .

Various other modifications of the invention are permissible.

What we claim as new is:

1. The combination of a water electrolyzer, means for causing a current capable of dissociating water to flow through the electrolyzer, and means controlled by said current for stopping the generation of gases 75 in event of the current starting to flow in the wrong direction.

2. The combination with a water electrolyzer and means for supplying the same with current to dissociate the water, of 80 means comprising a polarized device in circuit with the electrolyzer for causing opening of the electrolyzer in event of the dissociating current starting to pass in the wrong direction.

3. The combination with an electrolyzer, of a relay connected with the electrolyzer, and means controlled by said relay for stopping the operation of the electrolyzer in event of the dissociating current starting 90 to pass in the wrong direction.

4. The combination of an electrolyzer and its circuit, an electro-magnetic switch for opening and closing said circuit, a circuit for operating said switch, and a polarized 95 relay connected with the electrolyzer and controlling said switch-operating circuit.

5. The combination of an electrolyzer, a supply circuit therefor, a main switch for opening and closing said circuit, a hand re-set relay controlling said main switch, and a polarized relay connected with the electrolyzer circuit and operating through the hand re-set relay to control the main 100 switch.

6. The combination with an electrolyzer and its circuit, of a relay and means operated thereby for opening said circuit in event of current starting to flow in the wrong direction, said relay being connected with the electrolyzer circuit at the electrolyzer. 110

7. The combination with an electrolyzer, of a shunt in the electrolyzer circuit at the electrolyzer, a relay connected with the terminals of said shunt, and means whereby 115 said relay causes stopping of the operation of the electrolyzer in event of the dissociating current starting to flow in the wrong direction.

8. The combination with an electrolyzer 120 and its circuit, of a main switch for opening and closing the electrolyzer circuit, a circuit for operating said main switch, separate switches in said operating circuit, a polarized relay connected with the electrolyzer and controlling one of said switches in the main switch-operating circuit, and a potential relay connected in shunt to the electrolyzer circuit and controlling the other of 125 said switches.

9. The combination of a cell for the electrolysis of water, an electrolyzer circuit, a source of electric energy for causing current to flow through the cell to dissociate the water, and means for opening the electrolyzer circuit in event of the potential of the source falling to such low value that discharging would occur.
10. The combination of a cell for the electrolysis of water, an electrolyzer circuit, a source of electric energy for causing current to flow through the circuit and cell to dissociate the water, a potential relay having its coil connected across the source, a circuit controlled by said relay, a main switch in the electrolyzer circuit, and means in the circuit controlled by the potential relay for operating said main switch.
11. The combination of a water electrolyzer, an electrolyzer circuit, a source of electric energy for supplying the same with current, a main electro-magnetic switch controlling the electrolyzer circuit, a potential relay having its coil connected across the source, a hand re-set relay, said relays jointly controlling said main switch, and a polarized relay connected with the electrolyzer and controlling said hand re-set relay.
12. The combination with an electrolyzer and its circuit, of a motor-generator set for supplying the same with current, a starter for the motor, a circuit having a gap adapted to be closed by the starter toward the completion of its operation, and means in the latter circuit for closing the electrolyzer circuit.
13. The combination with an electrolyzer, a gasometer connected therewith, a pressure
- tank, and compressing apparatus connected to withdraw gas from the gasometer and compress the same into the pressure tank, of an upper limit switch controlled by the gasometer and means controlled by said switch for shutting down and starting up the electrolyzer, a lower limit switch controlled by the gasometer and means controlled by this switch for starting and stopping the compressing apparatus, and a pressure responsive device connected with the pressure tank and also controlling said compressing apparatus.
14. The combination of a water electrolyzer, means for supplying the same with current to dissociate the water, and electrical means in circuit with the electrolyzer for stopping the supply of current thereto in event of the dissociating current starting to flow in the wrong direction.
15. The combination with an electrolyzer and its circuit, of a motor generator set for supplying the same with current, a relay in circuit with the electrolyzer, and means whereby said relay opens both the electrolyzer and the motor circuits in event of the dissociating current starting to flow in the wrong direction.
16. The combination with an electrolyzer and its circuit, of a motor generator set for supplying the same with current, a relay in circuit with the electrolyzer, and means whereby said relay breaks the motor circuit in event of the dissociating current starting to flow in the wrong direction.

HENRY R. SWARTLEY, JR.
LOUIS LARSEN.
